UNITED STATES PATENT OFFICE

162,246

CHILDREN'S ROCKER

James M. Smith, Washington, D. C.

Application April 27, 1950, Serial No. 9,527

Term of patent 7 years

(Cl. D34—15)

To all whom it may concern:

Be it known that I, James M. Smith, a citizen of the United States, residing at Washington, D. C., have invented a new, original, and ornamental Design for Children's Rocker, of which the following is a specification, reference being had to the accompanying drawing, forming part thereof.

Figure 1 is a view in side elevation of a children's rocker embodying my new design;

Figure 2 is a top plan view of the children's rocker embodying the design; and

Figure 3 is a front elevational view of the children's rocker embodying the design.

I claim:

The ornamental design for a children's rocker, as shown.

JAMES M. SMITH.
